HOWARD BROWN, OF SPRINGFIELD, MASSACHUSETTS.

MARKING DEVICE FOR PAPER.

1,248,258.

Specification of Letters Patent. Patented Nov. 27, 1917.

Application filed February 23, 1912. Serial No. 879,245.

To all whom it may concern:

Be it known that I, HOWARD BROWN, a citizen of the United States of America, residing at Springfield, in the county of 5 Hampden and State of Massachusetts, have invented new and useful Improvements in Marking Devices for Paper, of which the following is a specification.

This invention relates to improvements 10 in paper machines and has for its object the provision of means for water marking the paper in the process of its manufacture. The mark has the general characteristics of so called water marks, but is applied after 15 the paper has been thoroughly formed into a sheet but before the paper passes all of the drying rollers.

By use of the means here disclosed, a 20 mark of relatively intricate design and having fine lines, as compared with ordinary water marks, may be impressed in the paper by means of a suitable plate, such as an electrotype, and the rigid impression plate is so 25 mounted as to be adjustable and controllable in its pressure on the paper when the paper is in this partially formed state, the effect of the plate being to produce a mark which is very clear cut in its outlines and details.

30 In the particular embodiment herein disclosed, the roll carrying the stereotype plates may be moved endwise to shift the location of the plates so that in case the strip of paper shifts sidewise on the lower roll, the 35 dies can be moved correspondingly and the impression can thus be held exactly in the center of the sheet or localized as desired.

In the drawings forming part of this application,—

40 Figure 1 is a front elevation view of the marking or embossing roller, and illustrating a sheet of paper passing thereunder and over another or press roller.

Fig. 2 is a transverse, sectional view on 45 the line 2—2 of Fig. 1 showing the stereotype plates which contain the figure to be embossed and which contact with the paper as it passes through the machine for transferring this figure or mark to the paper.

50 Fig. 3 is a view similar to Fig. 2 but showing the marking or embossing roller with its stereotype plate out of contact with the paper, and the supporting rings which are located on the end of this roller in contact 55 with the roller below.

Fig. 4 is a view showing the detailed con-

struction for adjusting the embossing roller longitudinally of the machine.

Fig. 5 is a diagrammatic view illustrating the path of the paper through a portion of 60 the paper marking machine.

The progress of the paper through the driers and the marking device is diagrammatically illustrated in Fig. 5.

Referring to the drawings in detail, a 65 designates the framework of a paper-making machine in which the rollers *b* and *c* are mounted, the boxes which receive the supporting shafts of these rollers being designated by the letters *d* and *e*,—the roller *c* 70 being the marking or embossing roller on which the stereotyped plates *f* are mounted or secured and the roller *b* being located below the roller *c* over which the sheet of paper passes, the paper at this point being 75 thoroughly formed but having not yet passed all of the drying rollers.

Secured to the box *e* is a weight device, by means of which the roller *c* is normally held downward into close contact with the 80 roller *b*. This weight device comprises an arm *h* which is secured to the framework *a*; and pivotally connected to this arm *h* is a second arm *i* that bears directly on the rod *j* which is secured to the box *e*. 85

Suspended from the arm *i* is a weight *k* which may be provided with additional weights, indicated at *k*¹. It should be understood that two weight devices are used,—one at each end of the roller. 90

Secured to the ends of the roller *c* are bearing or supporting rings *m* which are adapted to engage the roller *b*. The diameter of these rings is slightly less than the distance from the outer periphery of the 95 stereotype plates *f* so that when the sheet of paper is passing beneath the marking roll *c* the weight of this roll is transferred to the embossing plates *f*, the rings *m* then being away from the roll *g* as indicated in 100 Fig. 1.

Referring now to the longitudinal adjustment of the marking roll *c*, —*o* designates a U-shaped yoke-piece that is suitably secured to the frame *a* directly opposite the 105 ends *p* of the supporting shaft of the roll *c*. This U-shaped yoke piece is provided with a threaded opening through which passes an adjusting screw *q*, the inner end of which engages the end of the shaft *p*. The same 110 construction is provided at both ends of the roll *c* so that this roll may be moved in

either direction, as desired. A suitable lock-nut *r* is provided to retain the screw *q* in its adjusted position.

The roll *c* is driven by any suitable train 5 of gearing, as illustrated at the right-hand end of Fig. 1,—designated by the letter *s*.

From this construction, it will be seen 10 that I have provided a marking device which can be readily adjusted so as to accurately position the plates *f* with reference to the sheet of paper which is passing through the machine, and so that the mark will always appear in the same position on 15 each sheet, when the paper is cut into desired sizes.

What I claim, is:—

1. In a paper making machine, means for 20 impressing a water mark on the paper when the latter is in a damp condition, comprising a roll having a rigid arcuate design plate extending beyond the surface thereof, means for adjusting said roll, whereby during the operation of the machine said design plate will come into forcible periodic 25 contact with the paper, means comprising rings on the roll for maintaining it in position when the design plates are out of contact with the paper.

2. In a paper making machine, the combination of upper and lower co-acting cylinders, the former of which is movable both 30 vertically and axially end-wise relative to the latter; means for holding the upper cylinder under variable yielding pressure 35 against the lower cylinder, a series of arcuate projections affixed to the periphery of

the upper cylinder and provided with watermarking faces for impressions on the web in spaced longitudinal rows; a pair of collars extending continuously around the ends 40 of one cylinder and adapted to engage the face of the other cylinder when the lower cylinder is opposite a space between said projections, to support the upper cylinder out of contact with the lower cylinder at 45 such time, and means for retaining said upper cylinder in its longitudinally adjusted position.

3. The method of marking paper in the process of its manufacture which consists 50 in subjecting the paper before it is completely dried to the action of a hard unyielding non-heating backing roll and a pressure roll having a hard design surface thereon and applied against the paper on 55 said backing roll with a heavy regulable pressure.

4. The method of marking paper stock in the course of its transformation from pulp to finished paper, which consists in squeezing 60 the paper under heavy pressure, after it has been thoroughly formed but before it passes all of the drying rolls, between a hard impression surface and an unyielding non-heating backing roller, whereby clear-cut mark is communicated to the paper and 65 subsequently baked in and rendered permanent.

HOWARD BROWN.
